UNITED STATES PATENT OFFICE.

WILLIAM T. GOLDSMITH, OF ATLANTA, GEORGIA.

BOTTLE.

SPECIFICATION forming part of Letters Patent No. 243,547, dated June 28, 1881.

Application filed April 8, 1881. (Model.)

To all whom it may concern:

Be it known that I, WILLIAM T. GOLDSMITH, of Atlanta, in the county of Fulton and State of Georgia, have invented a new and Improved 5 Bottle, of which the following is a specification.

The object of my invention is to facilitate dispensing medicines and other liquids, especially such as are to be poured out in drops.

In the accompanying drawings, Figure 1 is 10 a side elevation of my improved bottle. Fig. 2 is a longitudinal sectional elevation of the same, showing it in a horizontal position. Fig. 3 is a rear elevation of the same, showing the air-channel. Fig. 4 is an end elevation of the 15 same. Fig. 5 is a rear elevation of my improved vial, showing the air-channel and enlarged base.

Similar letters of reference indicate corresponding parts.

20 The bottle A has a conical or pyramidal shape, so that the greater part of the weight of the liquid in the vial will be concentrated at the base of the same, thus giving the bottle or vial a much better bearing and protecting 25 it from being thrown over as easily as the bottles in use at present. This bottle has an inclined neck, B, with a lip, C, or a bead, D, at the lowest point of the edge to facilitate pouring the liquid from the vial in single drops. If 30 the neck of the vial is inclined the flow of the liquid can be controlled much better than if the neck is straight. As is shown in Fig. 2, the liquid rests mainly on the inclined side of

the bottle, and as it cannot flow up this inclined surface very small quantities of the liquid 35 can be drawn by slightly lowering the neck of the vial. The vial is provided with an air-channel, E, for conveying air into the interior of the vial to prevent bubbling of the liquid. The air can pass through this channel from the neck 40 to the extreme rear end of the vial. The cork F is secured in the neck of the vial by means of a cord or wire, G, catching on a projection, H, of the neck of the vial.

If desired, the base of the vial may be provided 45 with an enlargement, J, to give the vial a better bearing.

The side of the vial is provided with a recess, L, to receive a cork, K, for the purpose of easing the shock when the vial tumbles 50 over and for preventing the entire contents of the vial from flowing out in case the vial is accidentally upset. The cork K is also used to support the middle of the vial while dispensing in the sick person's room. 55

Having thus fully described my invention, I claim as new and desire to secure by Letters Patent—

In a drop-vial, the cork-socket L, arranged on the side opposite to that on which the weight 60 or projection J is placed and under the bead D, as and for the purpose specified.

WILLIAM THOMAS GOLDSMITH.
